UNITED STATES PATENT OFFICE.

WESLEY B. STATON, OF GRAY, SASKATCHEWAN, CANADA.

PICTURE-PUZZLE.

1,300,891.

Specification of Letters Patent. Patented Apr. 15, 1919.

Application filed May 17, 1918. Serial No. 235,152.

To all whom it may concern:

Be it known that I, WESLEY B. STATON, a British citizen, residing at Gray, Province of Saskatchewan, Dominion of Canada, 5 have invented certain new and useful Improvements in Picture-Puzzles, of which the following is a specification.

This invention relates to puzzle pictures and has for its object the provision of a 10 simple and inexpensive device which may be employed for the entertainment and amusement of young children, and which may incidentally be utilized as an advertising medium. The invention seeks to provide a device which will not be bulky and which may be readily handled by very small 15 children so as to hold their attention and prove instructive to them. A further object of the invention is to provide a simple device by which a plurality of pictures may be formed in the use of a single toy.

The invention is illustrated in the accompanying drawings, in which—

Figure 1 is a plan view of the puzzle picture showing the holder opened and one picture formed;

Fig. 2 is an enlarged section on the line 2—2 of Fig. 1 with the cover or holder folded;

Fig. 3 is a plan view of the device fully 30 opened or spread out;

Fig. 4 is a section on the line 4—4 of Fig. 3;

Fig. 5 is a section on the line 5—5 of 35 Fig. 3.

In carrying out my invention, I preferably provide a case or cover consisting of two leaves 1 and 2 which may be a single integral blank of stout paper, leather or 40 any other flexible material so that it may be readily folded, as indicated at 3. Upon the inner face of one of the leaves, I secure by any suitable adhesive a cruciform sheet which may be of muslin or other textile 45 fabric or paper or of any other light, cheap and flexible material. The central portion or body 30 of this cruciform blank will be secured to the inner face of one leaf of the cover throughout its extent and the edges 50 or wings of said blank will be longitudinally divided, as indicated at 4. Upon the outer face, or that face of each wing which will be opposed to the inner face of the cover when the device is fully spread, I 55 provide a plurality of pictures or picture sections 5 and each picture section will be

equal in area to one-half of the divided wing upon which it appears. Upon the outer half of the opposite face of each wing, I provide a picture section 6. I have 60 illustrated the picture sections as consisting of squares of thin card board or paper secured to the flexible wings by adhesive, but it will be understood that the picture sections may be printed or otherwise produced 65 directly upon the fabric of the wings. It will also be understood that the picture sections are so arranged that each section represents one-fourth of a particular picture and as there are six picture sections upon 70 each wing of the cruciform sheet in the illustrated embodiment of the invention, six complete pictures may be made with the toy shown in the drawings.

The pictures are to be formed by folding 75 the several wings or portions of the wings over onto the rectangular base of the cruciform body so that the four sections of the desired picture will be brought together. To add to the interest taken by the child in 80 the manipulation of the several wings, the picture sections are not arranged in any regular series, except in so far as may be necessary to permit folding of the several wings or tongues so as to bring the respective quarters of any picture into the proper relation. In Fig. 1 is shown a picture of 85 three geometrical figures, the sections of which have been brought together in proper relation. By referring to Fig. 3, it will be 90 noted that one section of this picture appears upon the inner face of the upper right hand branch of the upper wing of the flexible body or picture carrier, while the diagonally opposite section of the picture 95 is provided upon the inner face of the lower branch of the left hand wing of the picture covering body, and the other sections of the picture are upon the outer faces of the remaining tongues. The child using the puzzle 100 is consequently required to exercise some little ingenuity in folding the tongues so as to produce the sought for picture. When the device is not in use, the several wings may be folded into superposed relation and 105 the cover closed, as shown in Fig. 2, so that the pictures will be protected against damage and the device may be put away in a small place. All the pictures are formed by folding the several wings into superposed relation upon the central body but it 110 is possible to so dispose the portions of the

several pictures that the wings will not always be folded in the same manner or in the same sequence. Those portions of the flexible picture carrier which are not utilized for picture sections may have advertising printed thereon or the entire picture carrier may be covered with advertisements, and the principles employed in producing pictures utilized to bring sections together to make a connected advertisement.

Having thus described my invention, what is claimed as new is:

1. A puzzle consisting of a cruciform

body of flexible material having its wings divided longitudinally and having sections of pictures displayed upon the branches of its wings.

2. A puzzle comprising a cruciform body of flexible material having its wings longitudinally divided and having a picture section displayed upon the inner face of each branch of each wing at the free end thereof and having a plurality of picture sections on the outer face of each said branches.

In testimony whereof I affix my signature. 25
WESLEY B. STATON. [L. S.]
